CHARLES W. WYMAN, OF CLAREMONT, NEW HAMPSHIRE, ASSIGNOR TO SULLIVAN MACHINERY COMPANY, A CORPORATION OF MASSACHUSETTS

MOTOR CONTROLLING APPARATUS

Application filed January 2, 1929. Serial No. 329,929.

My invention relates to motor controlling apparatus.

The general object of my invention is to provide improved means for controlling reversible motors. It is a primary object to provide improved controlling apparatus for electric driving motors involving improved interlocking mechanism for a reverse switch, preventing reversal of the latter at times when such reversal would result in the breaking at the reverse switch contacts of circuits through which substantial currents are flowing. Particularly when automatically controlled starting resistance cutting out systems are employed is there a likelihood of the interrupting of large currents at the reverse switch contacts unless safety devices are provided, for should a contactor stick the reverse switch might be called upon to interrupt the full line current, which might result in short-circuiting the reverse switch and burning up of the latter. It is an object of my invention to provide improved means for preventing operation of the reverse switch under such conditions. It is a still further object of the invention to provide improved interlocking mechanism for the reverse switch controlled by an electro-magnet connected in such a manner that the regenerative current present due to the continued rotation of the motor cannot be broken at the reverse switch contacts. In an approved form the reverse switch lock magnet may be connected directly across the armature. A still further object of the invention is to provide an improved locking device for a common operating element for both a reverse switch and a pilot switch which controls automatic controlling apparatus located at a point remote from the reverse switch, this improved locking device operating, while current flow in the motor continues, to prevent movement of the controlling element to a position effecting reversal of current in the motor while permitting sufficient movement to effect control of the pilot switch. Still another object of the invention is to provide improved means for preventing reversal of the motor while the latter is running at generating speeds. Other objects and advantages of my inven-

tion will appear during the course of the following specification and claims.

In the accompanying drawings I have shown for purposes of illustration one form which my invention may assume in practice. 55

In these drawings,—

Fig. 1 represents a view generally in plan, the machine casing being broken away to show the illustrative embodiment of my improved reverse switch and controlling elements. 60

Fig. 2 is a central vertical section through the illustrative embodiment of my improved reverse switch and interlock, on line 2—2 of Fig. 1. 65

Fig. 3 is a transverse section through the machine casing on line 3—3 of Fig. 2, showing the illustrative embodiment of my improved reverse switch interlock in elevation. 70

Figs. 4, 5 and 6 are diagrammatic views of the illustrative embodiment of the reverse switch and associated elements, the reverse switch being shown in its different positions. 75

Fig. 7 is a wiring diagram illustrating the illustrative embodiment of my improved reverse switch and interlock as connected to a controlling apparatus located at a point remote from the motor. 80

In a preferred form of my invention I have provided a reverse switch of rugged construction having an operating element which when moved in either direction from a neutral position automatically closes a pilot switch. This pilot switch closes a control circuit for automatic controlling apparatus located at a point remote from the motor, operating to place the motor across the line through resistance and gradually cut out the resistance. A movable plunger is arranged adjacent the common control element for the reverse switch and pilot switch and is actuated by an electromagnet into interlocking relationship with the controlling element when said magnet is energized. This interlock while permitting a limited movement of the controlling element, sufficient to enable change in position of the pilot switch, prevents sufficient movement to separate the reverse switch contacts until the electromagnet is deenergized. The coil of this magnet 100

is connected directly across the armature terminals so that the magnet is energized until the motor comes nearly to a standstill because of the voltage generated in the armature rotating in the self generated magnetic field. When the motor comes to a standstill this interlock automatically releases, permitting the reverse switch to be moved to its opposite position for effecting reversal of the 10 motor.

In the specific embodiment of my invention illustrated in the drawings I have shown a machine frame 8 in which may be mounted a control shaft 9 extending into the interior of 15 the casing and having on its operating end outside the casing a manual controlling element 10. Reverse switch mechanism is attached to the machine casing by means of a suitable bracket 11 and bolts 12. This 20 bracket has a vertically projecting portion 13 which provides a recess 14 forming a housing for a part of the movable switch actuating element 15. A bearing plug 16 fixed to the stationary bracket projects into 25 a recess 16' in the movable member 15, and a spring 17 mounted between said plug and recess acts against the movable element 15 to hold the movable contacts of the reverse 30 switch in engagement with the stationary contacts. This switch carrying element 15 may be constructed of any suitable insulating 35 material such as bakelite or hard rubber. A pair of arcuate movable switch elements 18 and 19 of conducting material are loosely connected to member 15 by small lugs 20 and 21 projecting into recesses 22 and 23 respectively in member 15. The stationary contacts of the reverse switch are secured to a 40 stationary plate 24 of insulating material by means of bolts, two of which are indicated in Fig. 2 at 25 and 26. These bolts have mounted thereon nuts 27 and 28 so that they may serve as terminals for connections to the power lines and armature. Between the 45 plate 24 and bracket 11 there is mounted an intermediate member 29 which, together with stationary plate 24, forms a housing for the reverse switch. The plate 24 and member 29 are secured to the upstanding portion 13 of 50 the bracket 11 by any suitable means such as bolts 46. A gear 30 is formed integral with the switch carrying member 15 and is adapted to mesh with a pinion 31 on the operating shaft 9. It is of course not necessary to have 55 the teeth in gear 30 extending completely around the periphery of the member 15, since only a segment of the gear will ever be brought into mesh with the operating pinion.

In Fig. 1 particular attention is directed to 60 the manner in which the operating handle 10 is mounted on the control shaft. A key 32 connects the handle to the shaft so as to prevent relative rotation but permit a limited amount of longitudinal sliding movement.

65 On the exterior surface of the hub of handle

10 there are formed a plurality of grooves 33 and 34 connected by a longitudinal groove 35, and a stationary pin 36 suitably mounted on the frame of the machine engages in the grooves so as to prevent rotation beyond the central or neutral position without a pause to slide the handle longitudinally of the shaft.

100 My improved interlocking mechanism for the reverse switch will now be described. As best shown in Figs. 2 and 3, the switch actuating element 15 has formed therein a pair of arcuate recesses 37 and 38 either of which is adapted to receive the end of a locking plunger 39. An electromagnet having a coil 40 housed in a casing 41 is fixed directly to the bracket by means of a threaded stud 42. A movable armature 43 is mounted on the casing 41 and directly connected to plunger 39 by a nut 44.

80 A spring 45 normally holds the armature 43 and plunger in the retracted position, as shown in Fig. 2, where they will not interfere with operation of the switch actuating member 15. However, when the coil 40 of the electromagnet is energized, the armature will be attracted and the end of plunger 39 will engage in recess 37 or 38, depending on the position of the reverse switch, and control the movement of the switch actuating element as will presently appear. For the purpose of preventing accidental displacement of the 85 switch actuating element 15 from either of its "on" positions, there is provided a small plunger 47 having a conical head adapted to engage in conical recesses in the switch actuating element and resiliently held in engagement with these recesses by a spring 48.

90 The switch for controlling the pilot circuit of the remote controlling apparatus as before stated is arranged to be actuated by the same operating element as the reverse switch and is herein shown in Fig. 3 at 49. The terminals which connect to the pilot circuit are indicated at 50 and 51, the switch 49 being pivotally connected to one of these terminals and normally held open by spring 52. The lower side of switch 49 rests on the teeth of gear 30 and as indicated in dotted lines in Fig. 3, a number of these teeth are cut away to form an arcuate portion 53 of reduced radius which will permit control switch 49 to drop to open 95 position when the reverse switch operating element is in neutral position or within a certain predetermined angle at either side of neutral position.

100 Attention is now directed to the diagrams shown in Figs. 4, 5, and 6. Fig. 4 shows the reverse switch in neutral position. A pair of stationary contacts 54 and 55 diagonally opposite each other connect to power lines 56 and 57 respectively. The other pair of stationary contacts 58 and 59, also arranged diagonally opposite each other and midway between contacts 54 and 55, connect to the armature by means of wires 60 and 61 respectively, the armature being indicated at 62.

In Fig. 4 the movable contacts 18 and 19 engage only the pair of contacts 54 and 55 connected to the power lines and therefore the switch is in neutral position.

The operation of my improved reverse switch controlling mechanism to this point will now be described. With the parts shown in neutral position as indicated in Figs. 1 to 4 inclusive, the electromagnet 40 is deenergized and plunger 39 is in its retracted position. The movable switch elements 18 and 19 are touching only the pair of stationary contacts connected to the power lines and the pilot switch 49 is in open position, resting on the cutaway portion 53 of the gear 30. The operator now manipulates the control handle 10 in one direction or the other, depending on the direction of motor rotation which he desires, and the stationary pin 36 engages in groove 33 or 34. Assume that the operating element is turned so as to bring the movable contacts in the position shown in Fig. 5. The control circuit switch 49 has moved to closed position due to engagement with full length teeth on gear 30, and recess 37 is in position permitting engagement with plunger 39. During opposite direction of motor rotation the plates 18 and 19 are in the positions indicated in Fig. 6 and plunger 39 engages in recess 38. The pilot switch 49 is automatically closed on turning the reverse switch member in either direction to effect either direction of motor rotation. Now if the operator attempts to move the switch from the position of Fig. 5 to the position of Fig. 6 or vice versa, the length of recesses 37, 38 is such as to permit only a limited movement sufficient to cause opening of the control switch but not sufficient to break the main circuit, until the plunger 39 is retracted by its spring 45.

Referring now to the wiring diagram of Fig. 7, the units located at the machine are illustrated in the left hand portion of the figure and all the equipment in the right hand part of the figure may be located at any convenient remote point as in the entry of a mine and connected to the units on the machine by only three wires, as in a cable 85. This automatic remote control system is described in detail in my copending application Serial No. 243,964, filed Dec. 31, 1927, and will be herein described as briefly as possible, and if a more detailed description is desired, reference may be had to the aforesaid application. The motor in this figure is indicated at 62 and it will be noted that coil 40 of the electromagnet is connected directly across the armature terminals by a pair of wires 63 and 64. The series field is indicated at 65 and the shunt field at 66, the reverse switch being indicated diagrammatically at 67 and the pilot switch at 49. The equipment included in the automatic controlling apparatus located at a point remote from the

machine includes a plurality of resistance controlling contactors 68, 69, 70, and 71 and also a plurality of contactor controlling relays 72, 73, and 74. The resistance unit controlled by the contactors comprises in this instance three sections 75, 76, 77. An overload switch 78 is adapted to open the control circuit whenever there is an overload on the motor. In operation, the coil of relay 72 is immediately energized when the reverse switch is turned sufficiently to close a circuit, but not far enough to close the pilot switch, by power from the minus side of the line through reverse switch 67, motor 62, series field 65, line 79, through all the resistance units, lines 80, 81 and back to the positive side of the line through lines 82, 83, 84. Upon closure of pilot switch 49, the holding coil for the first contactor 68 is energized by power from the minus side of the line through switch 49, pilot wire 85 and line 86 and back to the positive side of the line through lines 87, 88, 89, 90. Closing of the first contactor 68 short-circuits the coil or relay 72, allowing the same to close a circuit after a certain interval of time required for the current to die out in relay 72, and power flows from pilot wire 85 through wire 91, relay 72, line 92, and energizes the coil of relay 69, the circuit being completed to the positive side of the line through wires 93, 88, 89, and 90. At the time of closing of the first contactor 68, the holding coil for relay 73 was energized by the voltage drop across section 77 of the resistance through lines 94, 95 and 80. When the second contactor 69 closes, the first portion of the resistance is cut out and at the same time the holding coil for relay 73 is short circuited, thereby allowing the same to close after a certain time interval required for the current to die out in the relay coil. In a similar manner contactors 70 and 71 are closed in turn and the motor placed directly on the line by the last contactor 71. At the time of closing of this contactor a switch 96 in the control circuit is opened, thereby deenergizing the holding coils for the first three contactors. However, the last contactor is kept energized by power from the pilot wire through relays 72 and 74. In my copending application Ser. No. 243,964 above referred to, I am presenting claims to an electric motor control system including a motor, main power lines leading thereto, an adjustable resistance, and apparatus for connecting the motor to the power lines through the resistance and for gradually cutting out the resistance as the motor comes up to speed, which apparatus comprises a plurality of switches, and electromagnetic means for operating them in a predetermined sequence, a control circuit for supplying current to the electro-magnetic means, and mechanical means for automatically breaking the circuit through all the

electro-magnetic means except the one for operating the last switch when the last switch closes, the control circuit having a manually operable switch.

5 As a result of my invention it will be apparent that an improved electric motor controlling mechanism has been constructed of simple and rugged units. The magnetic interlock will effectively prevent sufficient 10 movement of the reverse switch actuating element to allow opening of the reverse switch, and at the same time permit the pilot circuit to be controlled by the same actuating element, due to the lost motion connection between 15 the interlock and switch actuating element. The electromagnet of the interlocking mechanism will be supplied with sufficient energy to hold this armature retracted until the speed of the motor has been reduced to such an extent that the voltage 20 across the armature is practically zero.

Should a contactor stick, when an attempt was being made to effect reversal of the motor, the lock plunger would not be withdrawn, because the line current flowing 25 would flow in part through the coil 40 and prevent movement of the reverse switch to reverse position. If the motor is not running at a sufficient speed so that the counter 30 electro-motive force would hold the lock in, no detriment would result from reversing.

While I have in this application specifically described one form which the invention may assume in practice, it will be understood 35 that this form is shown for purposes of illustration and that the invention may be modified and embodied in various other forms without departing from its spirit or the scope of the appended claims.

40 What I claim as new and desire to secure by Letters Patent is:

1. In combination, a motor, a controlling device therefor, reversing mechanism for controlling direction of rotation of said motor, means operated on movement of said reversing mechanism for controlling said controlling device, and means for preventing movement of said reversing mechanism sufficient to effect reversal of said motor until 45 the motor has come substantially to a standstill but permitting enough movement to effect control of said controlling device.

2. In combination, an electric motor, controlling apparatus therefor, a reverse switch 50 for controlling direction of rotation of said motor, means operated directly by movement of said reverse switch for controlling said controlling apparatus, and means for preventing movement of said reverse switch sufficient to reverse current flow in said motor while the motor is rotating but permitting enough movement to effect control of said controlling apparatus.

3. In combination, an electric motor, controlling means therefor, a reverse switch for

controlling direction of rotation of said motor, means operated on movement of said reverse switch for controlling said controlling means, and a positive locking device for preventing movement of said reverse switch to a position effecting reversal of current flow in said motor while the motor is rotating at a substantial speed but permitting movement to effect control of said controlling means whereby the voltage which may be applied to the motor on reversal is materially reduced.

4. In combination, an electric motor, automatic controlling apparatus therefor, a reverse switch for controlling direction of rotation of said motor, a control switch operated on movement of said reverse switch in either direction from a neutral position for controlling said controlling apparatus, and means for preventing movement of said reverse switch to a position effecting reversal of current flow in said motor while the motor is rotating above a certain speed but permitting enough movement to effect operation of said control switch.

5. In combination, a source of power, a resistance, an electric motor, controlling apparatus for said motor for connecting the same to the source of power and for interrupting power supply including means for connecting the motor to the source of power through the resistance and automatically gradually cutting out said resistance, a reverse switch for controlling direction of rotation of said motor, a control circuit for controlling said controlling apparatus provided with a pilot switch, means automatically operating said pilot switch on predetermined movement of said reverse switch, and means for preventing movement of said reverse switch to a position effecting reversal of current in said motor while the motor is rotating at a predetermined speed but permitting movement of the reverse switch to effect control of said pilot switch and controlling apparatus.

6. In combination, an electric motor, automatic controlling apparatus therefor, a reverse switch for controlling direction of rotation of said motor, a pilot circuit controlling said controlling apparatus, a pilot switch in said circuit automatically operated on movement of said reverse switch from neutral position to either of its "on" positions for setting said automatic controlling apparatus into operation, and electrically operated positive locking means for preventing movement of said reverse switch from one of its "on" positions to the other while the motor is rotating at a substantial speed, but permitting movement of said reverse switch to effect operation of said pilot switch and controlling apparatus.

7. In an electric motor controlling apparatus, a motor, a manually operable reverse switch electromagnetic means for positively preventing movement of the reverse switch to

break the connections established thereby while the motor has motion above a predetermined speed, and means for energizing said electromagnetic means directly across the 5 armature terminals of said motor.

8. In an electric motor controlling apparatus, a motor, a manually operable reverse switch for effecting reversal of said motor, a mechanical interlocking mechanism for preventing movement of said reverse switch from one direction controlling position to another or to break the circuit therethrough but permitting a limited movement of said reverse switch, electromagnetic means for actuating 10 said interlocking mechanism to interlocking position when energized, and a circuit connected directly across the armature terminals for energizing said electromagnetic means.

9. In an electric motor system, a source of 20 power, a resistance, a motor, controlling apparatus for connecting the same to the source of power and for interrupting power supply including means for connecting said motor across the line through the resistance and automatically gradually cutting out said resistance, a pilot circuit for setting said automatic apparatus into operation provided with a pilot switch, a manually operable reverse switch for controlling said pilot switch and 25 direction of rotation of said motor, interlocking mechanism allowing movement of the reverse switch to effect control of said pilot switch but preventing movement from one direction controlling position to the other while 30 the motor is rotating at a substantial speed, an 35 electromagnet for rendering said interlocking mechanism effective when energized, and a circuit for energizing said electromagnet by current flow through said armature.

10. In combination, an electric motor, controlling apparatus therefor, a pilot switch for controlling said controlling apparatus, reverse switch means for controlling direction of rotation of said motor, a common operating 40 element for said pilot switch and said reverse switch means, and interlocking mechanism for preventing movement of said operating element to a position effecting reversal of current flow in said motor while the motor is rotating at a substantial speed but permitting movement to effect operation of said pilot switch.

11. The combination specified in claim 10 wherein said interlocking mechanism comprises a plurality of elongated recesses in said element, a plunger adapted to engage in either of said recesses to permit only a limited movement of said operating element, and an electromagnetic for actuating said plunger to 45 interlocking position energized by voltage across the armature terminals.

12. In combination, an electric motor, controlling apparatus therefor, a pilot circuit for said controlling apparatus, a pilot switch in said circuit, reverse switch means for con-

trolling direction of rotation of said motor, a common operating element for said pilot switch and said reverse switch means, interlocking mechanism for permitting movement of said operating element sufficient to control 70 said pilot switch but preventing sufficient movement to reverse current flow in the motor while rotating at a substantial speed, electromagnetic means for operating said interlocking mechanism to effective position, and means 75 for controlling said electromagnetic means in response to voltage generated in the armature during rotation.

13. In an electric motor controlling apparatus, a reversible motor, a manually operable reverse switch, electromagnetic interlocking means for preventing movement of the reverse switch from one direction controlling position to the other while the motor has motion above a predetermined speed, means for 80 energizing said electromagnetic means by voltage across the armature terminals during motor rotation, and means for preventing immediate reversing by said reverse switch after release of said interlocking means. 90

14. In combination, a reversible electric motor, controlling apparatus therefor, a pilot switch for controlling said controlling apparatus, a reverse switch for controlling direction of rotation of said motor, common operating means for said pilot switch and reverse switch, interlocking mechanism for preventing operation of said reverse switch from one direction controlling position to the other while permitting operation of said pilot 100 switch while the motor has motion above a predetermined speed, electromagnetic means for controlling said interlocking mechanism in response to voltage across the armature terminals, and mechanical means cooperating with said common operating means for preventing uninterrupted movement of said reverse switch after release of said interlocking mechanism. 105

15. In combination, an electric motor, controlling apparatus therefor, a pilot switch for controlling said controlling apparatus, reverse switch means for controlling direction of rotation of said motor including relatively movable contacts, a common operating element for said pilot switch and said reverse switch means operable to operate said pilot switch only subsequent to movement of said reverse switch to a circuit establishing position, and interlocking mechanism for preventing movement of said operating element to effect breaking of a circuit at the reverse switch contacts while the motor is rotating at a substantial speed but permitting movement of said operating element to effect restoration 115 of said pilot switch to its initial position. 120

16. A motor, lines for supplying current thereto, a switch movable to effect a predetermined relation between the terminals of the motor to prepare the same for rotation in a 125

- predetermined direction on line current supply thereto, a switch movable to establish and to interrupt flow of line current to said motor, means movable to operate said first mentioned switch and thereafter said second mentioned switch and reversely movable to effect their opening in reverse order, and means for preventing reverse movement of said first mentioned means to effect opening of said first mentioned switch while said motor is rotating above a predetermined speed but permitting movement thereof to effect opening of said second mentioned switch.
17. In combination, a motor, a switch closed to effect motor operation and opened to stop the motor, a reversing switch, and common operating means for said switches having a neutral position and movable in opposite directions therefrom and operative on predetermined movements in opposite directions from said neutral position to move said reversing switch to its positions for establishing circuits to effect operation of said motor in opposite directions and on further predetermined movements from said neutral position in either direction to effect closure of said first mentioned switch, and means for controlling movements of said operating means towards neutral position preventing movement of said reversing switch to break circuits established by its movement from neutral position while said motor is rotating at a rate above a predetermined speed.
18. In combination, a motor, a switch closed to effect motor operation and opened to stop the motor, a reversing switch, and common operating means for said switches having a neutral position and movable in opposite directions therefrom and operative on predetermined movements in opposite directions from said neutral position to move said reversing switch to its positions for establishing circuits to effect operation of said motor in opposite directions and on further predetermined movements from said neutral position in either direction to effect closure of said first mentioned switch, and means for controlling movements of said operating means towards neutral position preventing movement of said reversing switch to break circuits established by its movement from neutral position while said motor is rotating at a rate above a predetermined speed including electro-magnetically controlled locking means supplied with current whenever the motor is rotating above a predetermined speed.

In testimony whereof I affix my signature.

CHARLES W. WYMAN.
